UNITED STATES PATENT OFFICE

AARON W. ROBERTS, OF DALLAS, TEXAS

DESIGN FOR A SEPULCHER COMPASS OR ANALOGOUS ARTICLE

Application filed March 24, 1931. Serial No. 39,225. Term of patent 14 years.

To all whom it may concern:

Be it known that I, AARON W. ROBERTS, a citizen of the United States, residing at Dallas, in the county of Dallas and State of Texas, have invented a new, original, and ornamental Design for a Sepulcher Compass or Analogous Article, of which the following is a specification, reference being had to the accompanying drawings, forming part thereof.

Figure 1 is a perspective view of the article, showing my new design;

Figure 2 is a side elevational view; and

Figure 3 is a longitudinal sectional view.

I claim:

The ornamental design for a sepulcher compass or analogous article as shown.

AARON W. ROBERTS.
